UNITED STATES PATENT OFFICE.

JOSEPH H. KONIGSBERG, OF BROOKLYN, NEW YORK, ASSIGNOR TO VICTOR METAL PRODUCTS CORPORATION, OF BROOKLYN, NEW YORK, A CORPORATION OF NEW YORK.

TUBE FINISHING AND CAPPING MACHINE.

Application filed May 26, 1923. Serial No. 641,634.

This invention relates to machines for making collapsible metal tubes.

It has been customary, in machines of this character to mount an unfinished drawn tube on a mandrel manually, then to operate a suitable lever manually for setting tools into motion for finishing the end of the tube to be capped, said tube being capped manually thereafter, and manually removed from the mandrel.

The primary object of my invention is to perform the above mentioned operations of finishing and capping, automatically, by mechanism adjustable to various sizes of tubes, which mechanism while occupying little space, is capable of operation at high speed and with great efficiency.

A further object of this invention is the provision of means for automatically positioning a drawn tube so that certain operations may be performed thereon.

Further objects of this invention include the provision of means for automatically finishing both ends of the tube while said tube is in position; the provision of means for automatically capping said tube, and of means for ejecting the finished capped tube from the machine.

I attain the aforesaid and other objects, which will appear hereinafter by the mechanism shown in the preferred forms in the accompanying drawings, in which,

Fig. 1 is a front elevation of my improved machine. Fig. 2 is a side elevation of the same. Fig. 3 is a top plan view of the same. Fig. 4 is a vertical section of the capping mechanism on the line 4—4 of Fig. 2, showing in dotted lines the positions assumed by some of the parts during the capping operation. Fig. 5 is a similar view of certain of the parts in the positions assumed thereby while the cap is being delivered to the grip of the capping fingers. Fig. 6 is a vertical section of the capping fingers and of the bearing therefor on the line 6—6 of Fig. 5. Fig. 7 is a side elevation and partial section of the cap hopper and chute. Fig. 8 is a side elevation and partial section of the tube-receiving carriage and of the means for operating said carriage. Fig. 9 is a vertical section of the lead screw and nut for returning the carriage to its initial position. Fig. 10 is a top plan view of the tube-re-

ceiving carriage and of the operating mechanism for placing said tube in position on the mandrel. Fig. 11 is a similar view showing the parts in the positions assumed thereby immediately after said tube has been placed on said mandrel. Fig. 12 is a similar view of the means for rocking the carriage into alignment with the mandrel for positioning the tube on the mandrel. Fig. 13 is a section on the line 13—13 of Fig. 2, showing part of the means for feeding one tube at a time from the tube slide, and Fig. 14 is a similar section on the line 14—14 of Fig. 2.

This invention contemplates the performance entirely automatically of the operations of finishing and capping a drawn tube as hereinbefore pointed out, and the preferred means therefor are shown and described herein.

In my improved automatic machine, the operator need only feed the drawn unfinished tubes to a tube reservoir, and feed caps into the cap hopper. The machine arranges the caps into a substantially vertical single row, and then removes the lowermost cap of the row and delivers said cap to the capping position. Meanwhile, the lowermost tube in the tube reservoir is fed by gravity to a carriage which positions the tube on a mandrel. The usual finishing tools trim the mounted tube to the proper length and thread the end to be capped. The cap is then put on the tube, which is dismounted from the mandrel by a blast of air.

In the practical embodiment of my invention, I prefer to provide a tilted slide 100 for feeding the unfinished drawn tubes by gravity. Suitable mechanism is provided for receiving one tube at a time and for mounting said tube on the mandrel 30. The caps meanwhile are aligned in a single row in the T-slot 25 of a cap chute 21 and a single cap is grasped by the capping fingers 46 and brought to the capping position, (Fig. 4). The cap feeding mechanism comprises the hopper 20 which terminates in the said cap chute 21, and mechanism operatively connected to said hopper for agitating the caps therein and causing said caps to assume the proper position in said chute. An agitator and cap receptacle 22 is revolubly mounted on said hopper 20, as by means of the shaft

23, and has a suitable belt groove 24 therein. Said receptacle may be rotated by a suitable belt driven from the main cam shaft 150, and engaging said groove 24, whereby the caps 5 are caused to arrange themselves in the groove 25 and the caps 26 are thereby delivered to the lower end 27 of said chute 21 one at a time. For allowing the cap to be taken out of said chute in a substantially 10 horizontal direction, an opening 47 slightly larger than the diameter of said cap, is made in the end 27 of said chute, but none of the caps are allowed to drop to the bottom of said groove and opposite said opening until 15 the capping mechanism is ready to grasp and remove the lowermost cap from the chute.

Means, which will soon be described, cooperate with the lower end 27 of said chute for grasping and transferring one cap 26 at 20 a time to the fingers 46, which are in turn operated to grasp said cap firmly and to carry said cap to a position in alignment with the finished end 28 of the tube 29 after said tube has been properly mounted on the 25 mandrel 30. The pair of fingers 46 are pivoted on a suitable bearing 60 as at 61 and 62, said fingers being adapted to oscillate about said pivots and in the grooves 63 of said bearing 60. Said bearing 60 is fastened to 30 the left end of the shaft 38 for revolute movement about said shaft while relative longitudinal movement of said shaft and said bearing is prevented by the pin 64 inserted therebetween. (Fig. 6.) The links 65 serve 35 to connect the right ends of the fingers 46 to the collar 66, which is slidably mounted on said shaft 38. It will be noted that the shaft 38 is supported in the bearing 35 for limited longitudinal movement in said bearing as 40 will be more fully described hereinafter. For sliding said collar 66 and therethrough oscillating the fingers 46 about their pivots 61 and 62, I provide the lever 67, pivoted on the bearing 35 at 169. The end 69 of said 45 lever engages the collar 66, while the end 68 of said lever 67 engages the collar 70, which is loosely mounted on the rod or shaft 34 and which is maintained in its uppermost position by a compression spring 71, ar- 50 ranged between the lower face of said collar and the upper surface of the bearing 35. For insuring correct alignment and accurate vertical motion of the rod 34 of the bearing 35 connected thereto, and of the shaft 38 55 and the parts carried thereby, I provide a guide 72 bifurcated at the right end 73 and secured at its other end to the upper end of the rod 34, said forked end 73 being in contact with and guided by the vertical guide 60 rod 74, suitably secured to the upstanding frame 50 of the machine. It will be seen that when vertical motion is given to the rod 34 said rod carries with it the bearing 35 and the capping fingers mounted thereon, and if 65 vertical movement of said rod 34 is resisted,

causes the lever 67 to rock about its pivot 169, whereby the fingers 46 may be opened or closed more tightly through the consequent movement of the collar 66 and the links 65 connecting said collar and said fingers, in a manner which will be described more fully hereinafter.

For delivering a cap 26 to the capping fingers 46 I provide a rod 75 slidably mounted for substantially horizontal movement in the bearing 76, secured to the end of the chute 21. The end 77 of said rod is preferably reduced in diameter sufficiently to enter one of the caps 26 when it is desired to push the lowermost cap through the opening 47. Said rod 75 is reciprocated longitudinally by means of the lever 200 actuated at its rear end by the cam 201, and having its front end forked to engage the collar 78, which is secured to said rod 75. For urging the shoulder 79, of the rod 75, formed by the reduced portion 77 of said rod, into engagement with the head of the cap 26, (Fig. 4), a compression spring 179, abutting at one end against said collar and confined at its other end in 90 the bracket 80, is provided. In the normal position of said rod 75 the larger or head portion of the cap 26 rests against the reduced end 77 while the remainder of said cap rests on the main body portion of said rod. A stop rod 39 is arranged in a longitudinal opening made centrally in the shaft 38, part of a second push rod 40 being inserted at the left end of said shaft into said opening. Said push rod terminates in a 100 button 44 preferably curved on the face thereof to correspond with the curvature of the outer face of a cap 26. A shoulder 41 on the rod 40, against which shoulder the compression spring 42 abuts, confines said spring 105 in the enlarged opening 43 in said shaft 38, said spring 42 serving to resist inward movement of the button 44, toward the right.

In order to adjust and control the movement of the shafts 34 and 38, I provide split 110 bushings 32 and 36 respectively therefor. The amount of the resistance by said bushings to the longitudinal movement of said shafts for the purpose which will soon appear, is varied by means of the adjusting 115 screws 33 and 37 respectively.

The operation of my improved capping device is as follows: It being assumed that the rod 75 is in its initial position as shown in Fig. 4, and that the fingers 46 are opened apart in the position shown in Fig. 5, the lever 200 through the cam 201 is operated to draw the rod 75 toward the left against the action of the spring 179. Withdrawal of the reduced end 77 and the cap-supporting 120 body-portion of the rod 75 from underneath the lowermost cap 26, is thereby effected, whereby said lowermost cap drops down into the position shown in Fig. 5 with the remaining caps of the row in the chute 21 125 130

aligned in a single row thereabove. The return movement of the cam lever 200 now causes the end 77 of the rod 75 to enter said cap, the shoulder 79 engaging the rim of the cap, and causes said end 77 to move said cap through the opening 47 of the chute end 27, into contact with the curved surface of the button 44. Continued movement of the cam and of the rod 75 toward the right 5 moves the button 44 and the rod 40 on which said button is mounted toward the right, against the action of the spring 42, the pressure on the bushing 36 being so adjusted that movement of the rod 40 takes place before longitudinal movement of the shaft 38 in said bushing 36 can take place. After the spring 42 has been compressed a predetermined amount so that the right end of the push rod 40 is stopped by the left end 10 of the adjustable stop rod 39, further motion of the rod 75 toward the right overcomes the resistance caused by the pressure of the split bushing 36 on the shaft 38. Said shaft 38 is therefore caused to move toward the right, carrying with it the finger bearing 60 and the fingers 46, whereby the links 65 are swung about their pivots on the collar 66 toward the vertical and the left ends of the fingers 46 are closed about the cap. It will 15 be understood at this time that the collar 66 cannot move under the influence of the longitudinal movement of the shaft owing to the fact that the collar 70, on which the lever 67 controlling said collar is mounted, 20 is in its uppermost position in contact with the lowermost face of the bearing. 25

The cam lever 200 is now operated by the cam 201 toward the left, withdrawing the rod 75 against the action of the spring 179, 30 to the position shown in Fig. 4, in which the lowermost cap of the row rests on said rod 75 in readiness for the repetition of the operation. Meanwhile, the cam 300 on the main shaft 150, operates the lever 301 pivoted at 302, and forked at its upper end 303, to cause the collar 70 to move downwardly. It will be seen that any such movement of 35 said collar 70 downwardly rocks the lever 69 in a direction which causes the collar 66 to be pressed even more tightly than before against the links 65, whereby the fingers 46 are urged still more tightly against the cap 26 held therein. The spring 71 arranged 40 between the collar 70 and the bearing 35 is so designed that when the lever 69 can no longer move the collar 66 toward the left, downward movement of the entire bearing 35, of the shaft 38 and of all the parts mounted on said shaft takes place, in spite 45 of the resistance of the split bushing 32 to said downward movement.

The shaft 34 continues to move downwardly under the influence of the cam 300 until the under shoulder 304 of the guide 50 65 72 abuts against the upper surface 305 of the

bearing 31, at which time further downward movement of the shaft 34 is prevented, the shaft or rod 34 having reached its lowermost position. The shaft 38 is now positioned coaxially with the mandrel 30 and 70 the capping of the tube 29 may now take place. However, the cam 300 continues to urge the collar 70 downwardly. This results in the compression of the spring 77 and in the rocking of the lever 69 so that 75 the collar 66 is urged against the links 65 to close the fingers tightly and to move said fingers together with the bearing 41, the shaft 38, the rod 40 and the cap mounted in the fingers, toward the left, a sufficient distance to apply the cap 26 on to the finished threaded end 28 of the rotating tube 29, whereby the cap is firmly screwed on to the end of said tube. 80

It will be noted that the fingers 46 together with the bearing 41, the links 65, and the collar 66 are all free to rotate about the shaft 38 if the pressure caused by the rotating tube 29 on the thread of the cap and tube end is too great for rapid threading, though it will be seen that the spring 71 and the cam 300 may be so proportioned that the cap 26 is fed on to the end 28 of the tube at a speed which is synchronized with the speed of rotation of said tube. It also will be seen that after the tube has been capped, and before the fingers 46 are opened to release the cap 26, rotation of the capped tube merely causes said fingers, together with the bearing 41, the links 65 and the collar 66 to 90 rotate as a unit without injury to any of the mechanism. 95

When the collar 70 starts on its upward return journey, the slightest movement of said collar first rocks the lever 69 about its pivot 169 causing the collar 66 to move toward the right, longitudinal motion of the shaft 38 being prevented by the tight bushing 36, and longitudinal motion of the shaft 34 being prevented by the tight bushing 32. 100 Only a slight movement of said collar 66 is required to draw the left end of the links 65 together, thereby rocking the fingers 46 about their pivots 61 and 62 and opening the left ends of said fingers to release the 105 cap. The pressure of the spring 42 is thereby suddenly transferred from the fingers and is concentrated through the push rod 40 upon the head of the cap, so that said cap is given the final pressure to secure it firmly in 110 position, the sudden additional pressure due to said spring 42 corresponding in effect to the final tap usually given to the cap by the operator with the palm of her hand on the completion of the manual capping operation. 115 Continued movement of the collar 70 upwardly serves to draw the collar 66 toward the right relatively to the shaft 38 until said collar abuts against the shoulder 85, the compression spring 71 being allowed to 120 125 130

tend itself. It is to be noted here that when the shaft 34 is in its lowermost position, the split bushing 36 causes sufficient pressure on the shaft 38 to prevent movement of said shaft during the movement of said collar 66 to the right and after collar has reached its extreme position to the right, and that thereafter upward movement of the collar 70 raises the shaft 38, the bearing 35 and the shaft 34 connected to said bearing up to the position indicated in Fig. 4, the fingers 46 however, at this time being opened, instead of in the closed position shown. This completes the cycle of the capping operation and all the parts are now again in their initial positions.

The means for feeding and mounting the drawn tube on the mandrel 30 will now be described. A tube slide 100 is tilted downwardly and toward one side so that any tube 29 placed therein will tend to roll toward the bottom and to slide toward a stop 101, the rolling and sliding continuing until the neck 102 of the tube is in contact with said stop. Additional tubes 29 placed above the lowermost tube will tend to straighten out the entire row, and will tend also to force the lowermost tube out of the slide, if said lowermost tube is not held in place.

Means are provided for allowing only one tube at a time to drop into the carriage 103.

Said means comprises a pair of gates or shutters 250 and 251, the former positioned rearwardly of the lowermost tube of the row, and the latter arranged forwardly of said tube, said gates being operated to move in opposite directions. The cam lever 252 pivoted at 253 and operated by the cam 260, is passed over the lever 254 and under the lever 255. Said lever 254 is pivoted at 256 at the end of the arm 257 which is suitably secured to the slide base 100, the extremity of said lever being fastened to the gate or shutter 250. The lever 255 is similarly pivoted at 258 on the arm 259 and carries the gate 251. The tension spring 261 tends to maintain the gate 250 in its lowermost position, while the tension spring 262 performs a similar function for the gate 251. Each of said gates 250 and 251 is suitably supported in a guide 263, each suitably secured to longitudinal member 264 of the slide.

For feeding a tube to the carriage 103 the front end of the cam lever 252 is raised, thereby raising the gate lever 255 about its pivot and lifting the gate 251 to allow the lowermost tube to drop into said carriage, the gate 250 not being moved. On the downward movement of the cam lever end, the lever 255 is released and is drawn down by the spring 262 to its lowermost position, while the gate lever 254 is removed to lift the gate 250 and to allow the next tube to roll down into contact with the gate 251 in

readiness to drop into the carriage 103 in its turn. On the upward movement of the lever 252, the spring 261 draws the gate 250 down to bar out the remaining tubes of the row.

Said carriage 103 is preferably V-shaped in cross section for accurately positioning the tube which drops thereinto. A bracket 104 secured at its lower end to the shaft 105 has two upstanding arms 106 and 107 terminating in bearings 108 and 109 respectively. The carriage 103 is pivotally mounted on said bearings, as by means of the shaft 110, passing through said bearings 108 and 109 and through the bearing 111, at the end 70 of the arm 112 extending from said carriage. Secured to said bearing 111 and said arm is the downwardly extending plate 113, by means of which the entire carriage may be rotated about the shaft 110. A second arm 75 114 extends substantially horizontally from the bearing 111 and is normally pulled downwardly by means of the tension spring 115 (Fig. 8). The lowermost end of the spring 115 is attached to the shaft 105 and serves 80 to urge the carriage 103 toward its uppermost position relatively to the bracket 104, by rotating said carriage about its pivot 110. Said shaft 105 is suitably mounted for longitudinal movement in the bearing brackets 85 116 and 117, suitably secured to the main frame of the machine. For urging said shaft 105 and the bracket 104 mounted thereon toward the left, (Fig. 1) when the tube is to be mounted on the mandrel I prefer to 90 use a flexible connection such as the rope 118, and weights as 119. The flexible connection or wire rope 118 may be passed around a suitable pulley as 120, which is supported by means of the bracket 121 suitably secured to the main frame of the machine. For causing longitudinal motion of the shaft 105 toward the right I prefer to 95 use a lead screw 122 suitably supported in the bearings 123 and 124 of the brackets 100 116 and 117 respectively, though it is obvious that equivalent means such as a cam, 105 may be used for this purpose. Said lead screw 122 is rotated through the sprocket 110 wheel 125 on the shaft 126, the chain 127 115 and the sprocket wheel 128 on the lead screw 115 shaft. Power is supplied to the drive shaft 126 through the pulley 129, operatively connected to a suitable source of power not 120 shown. The main cam shaft 150 is operatively connected to said drive shaft 126 by means of the cooperating gear wheels 130 and 131, a one revolution clutch 132 adapted to be set into motion for making only one complete turn of the cam shaft at a time, 125 being interposed between the gear wheel 130 and the cams on the shaft 150, whereby the various instrumentalities operated by said cams are caused to perform a complete cycle 130 of operations on each revolution of the shaft 130

150. It will be noted that the shaft 150 on which the various cams for causing operation on the drawn tube, are mounted, should not be allowed to rotate while the drawn tube in the carriage 103 is being mounted on the mandrel 30 though said shaft 150 may rotate while the empty carriage is being returned to its initial position. I provide a half nut 133 secured to the shaft 105 by means of a nut 233 and adapted to rock with said shaft into and out of engagement with the lead screw 122 for returning the bracket 104 and the carriage mounted thereon to its initial position at the right of the machine. For operating the clutch 132, the right end of the bell-crank-lever 136 is secured to the link 138 which is pulled by the tension spring 139 into engagement with a suitable beveled member 140 of the type usually employed in a one revolution clutch of the type shown. The co-operating members of said clutch 132 are urged into mutual engagement by means of the compression spring 141 on the shaft 150, the spring 139 aiding in holding the lever 138 against the member 140 for the purpose of causing the clutch members to engage each other. However, at the extreme end of the movement at the shaft 105 towards the left under the influence of the weights 119, the roller 134, carried by the pin 135 secured to said shaft, strikes the end 142 of the bell-crank-lever 136, rotating said lever about its pivot 137 and withdrawing the link 138 out of engagement with the beveled member 140 against the action of the spring 139. The compression spring 141 is then free to cause the engagement of the clutch members and the consequent revolution of the shaft 150. It will be understood that the pin 135 and the roller 134 carried thereby are so arranged on the shaft 105 that the clutch lever 138 is thrown only at the extreme end of the movement of the shaft 105 to the left, at which time the mounting of the tube on the mandrel has been completed, and the operation thereon by the trimming tool 144 and the threading tool 143 may be permitted in the usual manner through the cams 145 and 146 on the shaft 150.

On the movement of the shaft 105 toward the right under the action of the lead screw 122 the bell-crank-lever 136 is released, allowing the spring 139 to pull the link 138 into engagement with the clutch member 140, thereby disengaging the clutch parts and halting revolution of the shaft 150, after one complete revolution thereof has been made.

The various movements of the bracket 104 and of the carriage 103 during the operation of mounting a tube on the mandrel will now be taken up. In the initial position of the carriage 103 as shown at 147, Fig. 8, a tube is allowed to drop into said carriage from

the slide 100 by the means hereinbefore described. In this position of the bracket 104, the roller 148, carried by the pin 149, which is secured on the underside of the shaft 105, is held between the spring pressed slides 151 and 152 respectively (Figs. 1, 10, 11, and 12). The slide 151 is carried by the rod 153 mounted in the bracket 154 and is urged into its outermost position by the compression spring 155. The slide 152 is similarly mounted on the rod 156 carried by the bracket 157 and is urged toward its extreme left position by the spring 158 controlled by the cam lever 159 operated by the cam 161 through the collar 160.

After the tube has dropped into the carriage 103 the cam 161 causes the collar 160, the rod 156, and the slide 152 to move toward the right whereby the roller 148 is released and is caused to rock together with the shaft 105 and the bracket 104 about the center of said shaft 105 under the influence of the spring 155 until the position indicated by the full lines in Fig. 8 is reached, wherein the axis of the tube 29 is in accurate alignment with the axis of the mandrel 30.

To insure accuracy of alignment of the tube and mandrel a plate 162 having the substantially rectangular cam groove 163 there-in is secured to the frame of the machine in such a position that the roller 164 carried by the pin 165 which is secured to the shaft 105, is in the position shown by the dotted lines in Fig. 9, when the bracket and carriage are in their initial positions, so that said roller 164 is at the upper right hand corner of the groove 163. When the roller 148 is released by the slide 152 and the shaft 105 consequently rocked under the action of the spring 155, said roller 164 moves along the vertical part of the cam groove 163 into a position at the lowermost right corner of said cam groove into the position shown by the full lines in Fig. 9, the location of said roller in the vertical part of the cam groove determining the angular positions of the shaft 105 and of the carriage 103. Said roller 164 being now at the extreme right of the lower horizontal groove of the cam groove 163, the weights 119 are free to pull the shaft 105 bodily toward the left, carrying with it the carriage 103 and the tube 29 and causing said tube to position itself about the continuously rotating mandrel 30 until further movement of the carriage is prevented when the roller 164 reaches the end of the horizontal groove.

The end 230 of the mandrel 30 is adapted to enter the capped end of the tube, and is made preferably hexagonal or otherwise polygonal in cross-section, so that as the carriage is drawn at accelerated speed to the left by the weights 119, the adjustable screw 203 on the carriage rams the tip of the tube on said end 230, and the edges of said end cut

into the inside of said tip sufficiently to hold the tube firmly on the rotating mandrel during the ensuing operations thereon.

In this position the mounting of said tube has been completed and the clutch 132 becomes operative as hereinbefore described, to move the tool slides forwardly ready to commence operation upon the tube. A spring pressed roller 166 on the rod 167 is carried in advance of, and by one of the tool slides so that as said slide comes forwardly under the action of its operative cam, said roller engages the plate 113 of the carriage and rocks said carriage about its pivot 110 to remove said carriage against the action of the spring 115, from its position near the mandrel into the position shown by the dotted lines in Fig. 8 at 168. Near the end of the movement of the carriage 103 toward the left, the roller 148 strikes the hook 170 which is pivoted to the machine at 171, and rotates said hook about its pivot, thereby extending the spring 172. Said spring is connected to said hook at one end and to an arm 173 at its other end, the parts assuming the positions shown in Fig. 11, in which positions the mounting of the tube on the mandrel has just been completed.

When the rod 167 now comes forward to strike the plate 113 the bracket 104 is maintained in the position shown by the full lines in Fig. 8, by means of the hook 170 and the spring 172, whereon rotation of the carriage about the shaft 110 takes place. It will be understood that it is desirable to move the carriage 103 away from the mandrel 30 before the bracket 104 is rotated. By the means above described the bracket 104, through the roller 148, is held stationary during a part of the forward movement of the rod 167, until the plate 113 assumes the position shown by the dotted lines 168 in Fig. 8, in which the plate 113 is in contact with the bracket 104. As the tool slide is operated by its cam to bring the tool forwardly for operation on the tube 29, the plate 113 is first rotated and then after its limiting position has been reached, the bracket 104 is then rotated about the center of the shaft 105, whereby said shaft 105 is rocked together with the pin 165, and the roller 164 is carried in the vertical part of the cam groove 163 to the upper left hand corner of said groove. The half nut 138 is thereby caused to engage the lead screw 122, and the bracket 104 and carriage 103 are caused to assume the positions indicated in dotted lines at 174 Fig. 8, the bell-crank-lever 136 having meanwhile been rocked by the roller 134 and the clutch 132 set into motion. On the last part of the forward movement of the rod 167 the consequent rotation of the bracket 104 carries the roller 148 at the lower end thereof into the position shown by the dotted lines at 177 Fig. 11. The various tools are then operated by

the usual cams on the cam shaft 150 to finish the tube 29 in the usual manner, while the carriage 103 is being carried toward the right back toward its initial position, the roller 164 traveling in the upper horizontal portion of the cam groove 163. After the finishing tool has cut the tube to the proper length, a cylindrical waste piece 175 remains on the mandrel 30.

A pair of cutting fingers 189 on the carriage 103 serves to cut apart and remove from the mandrel the trimmed end 175. Since said fingers travel in advance of the carriage, it will be seen that even though the waste piece 175 is not completely cut and removed from the mandrel by said cutting fingers, said piece is at least pushed along the mandrel a sufficient distance to allow the tube to be properly mounted thereon.

Near the end of the movement of the carriage 103, bracket 104, and roller 164, to the right under the action of the lead screw 122, said roller 148 engages the inclined edge 178 of the slide 151 causing said slide to move rearwardly against the action of the spring 155, said slide and roller assuming the positions shown by the dotted lines at 180 Fig. 11. At the completion of the inward movement of said slide 151 the cam 161 operates through the lever 159 to move the collar 160 and the rod 156 and slide 152 carried thereby, toward the left into the position shown in Fig. 11. The half nut 133 now having reached the end of the lead screw 122 further movement of the shaft 105 and of the parts carried thereby toward the right cannot take place. The spring 155 acting through the slide 151 now functions to move the roller 148 forwardly into contact with the slide 152. Said forward movement though slight, is sufficient to entirely disengage the half nut 133 from the lead screw 122, the various parts now being again positioned in their initial positions, so that the cycle of operations may be repeated. It will be understood that during the movement of the shaft 105 toward the right the various cams on the cam shaft have caused the respective tools operated thereby to finish the tube and have withdrawn said tools into their initial positions ready for the throwing of the clutch 132 to begin another revolution.

The mandrel 30 is preferably continuously rotated and is provided with an opening 182 made longitudinally therethrough and connected, as by means of the pipe 183, to the pump 184 carried by the bracket 185 which is secured to the frame of the machine. Said pump may be operated by means of a suitable cam on the shaft 150 through the rod 185. The pump is operated so that on the completion of the finishing operations and after the removal of the tools and tool slides, air pressure is suddenly applied through the opening 182 of the mandrel and blows the

finished tube 29 from the mandrel 30 and into a suitable receptacle provided therefor.

It will be seen that my machine is readily adjustable to different sizes of tubes and caps. The adjustment may be easily accomplished by the substitution of a mandrel, cap hopper, cap fingers and tube slide of the size corresponding to the tube to be finished and capped, though the remaining parts of the machine need not be disturbed.

I do not wish to limit myself to the specific mechanism shown herein, as it is obvious that various changes such as the substitution of a cam for the lead screw acting to draw the carriage toward the right, the adaptation of my tube mounting means to a multiple spindle mandrel and the consequent elimination of much of the mechanism shown, and other changes which need not be mentioned here, may be made without departing from the scope of this invention.

I claim:

1. In a tube finishing and capping machine, a cap hopper, means for delivering a single cap at a time from said hopper to the capping position, a reservoir for thin collapsible tubes, means for delivering a single tube at a time from said reservoir into finishing position, comprising means for supporting said tube in finishing position, an oscillatory and reciprocatory tube carriage, means for delivering a single tube at a time to said carriage, and means for operating said carriage for causing said carriage to mount a tube on said supporting means, means for finishing said tube, and means for causing said cap delivering means to cap said tube.

2. In a tube finishing and capping machine, means for delivering a soft, thin, collapsible tube into finishing position, comprising a tube reservoir, means in spaced relation longitudinally and transversely of said reservoir for supporting said tube in finishing position, an oscillatory and reciprocatory tube carriage, means for delivering a single tube at a time from said reservoir to said carriage, means for oscillating said carriage from the tube receiving position thereof into alignment with said supporting means, and means for moving said carriage longitudinally until said carriage is under said supporting means for causing said carriage to mount a tube on said supporting means.

3. In a tube finishing and capping machine, a mandrel, means for mounting a soft, thin, collapsible tube on said mandrel, comprising an oscillatory and reciprocatory tube carriage, means for delivering a single tube at a time to said carriage, and means for operating said carriage.

4. In a machine of the character described, a cap hopper, cap gripping means, recipro-

catory means for ejecting a single cap at a time from said hopper, and within reach of said gripping means and for operating said gripping means to close on said cap, and means for moving said gripping means bodily in a direction substantially at right angles to that of the movement of said cap ejecting means, for delivering said cap into capping position.

5. In a machine of the character described, a reservoir, for thin, collapsible tubes, a mandrel spaced from said reservoir, a tube carriage, means for oscillating said carriage for carrying a tube from said reservoir to a position in alignment with said mandrel and means for reciprocating said carriage for mounting said tube on said mandrel.

6. In a tube finishing and capping machine, a cap hopper, means for arranging the caps in said hopper in a single vertical row, means adapted to grip a cap by the axial movement of said means for withdrawing the lowermost cap of said row, and means for moving said withdrawing means bodily in a direction substantially perpendicular to said axial movement for delivering said cap into capping position.

7. In a tube finishing and capping machine, a mandrel, a tube carriage for mounting a tube on said mandrel, means for capping said tube, and means for dismounting said capped tube from said mandrel.

8. In a tube finishing and capping machine, means for delivering a thin, collapsible tube into capping position, comprising a tube carriage substantially V-shaped in cross section, means for delivering a tube to said carriage, means for aligning said carriage, and means for moving said carriage for bringing said tube in capping position, and means for delivering a cap into capping position and for capping said tube.

9. In a tube capping machine, a cap hopper, a cap chute, means for arranging said caps in a single row in said chute, capping fingers, means for removing the lowermost cap of the row and for feeding said cap to said fingers, and means actuated by said cap removing means for closing said fingers about said cap, for delivering said cap into capping position, and for withdrawing said fingers from said cap.

10. In a soft metal collapsible tube finishing machine, means for supporting a tube, a tube carriage, means for oscillating said carriage for carrying a tube to a point in alignment with said supporting means, means for reciprocating said carriage for mounting said tube on said supporting means, and means for capping said tube.

11. In a machine for finishing soft metal collapsible tubes, means for supporting a tube, means for mounting said tube on said supporting means, and means for driving air through said supporting means for dis-

- mounting said tube from said supporting means.
12. In a machine for finishing soft metal collapsible tubes, means for supporting a tube for operation thereon, means for mounting said tube on said supporting means, means for capping said tube and means for dismounting said tube from said supporting means.
13. In a tube finishing and capping machine, a cap hopper, means for arranging the caps in said hopper in a single vertical row, a tube reservoir, means for feeding a single tube at a time from said reservoir, tube supporting means, means for mounting a tube on said supporting means, and means adapted to withdraw a cap from said row for capping said tube.
14. In a tube finishing and capping machine, means, free to rotate, for feeding a single cap at a time into capping position, tube supporting means, means for mounting a tube on said supporting means, means for finishing said tube, means for urging said cap-feeding-means toward said supporting means for capping said tube, and for withdrawing said cap-feeding-means after said tube has been capped, and means for dismounting said tube from said supporting means.
15. In a tube finishing machine, a mandrel, a tube carriage, means for oscillating said carriage into alignment with said mandrel, means for reciprocating said carriage toward said mandrel, means for withdrawing said carriage from said mandrel, and means for finishing a tube.
16. In a tube finishing and capping machine, a revolute mandrel, a carriage for mounting a tube on said mandrel, means for capping said tube, means for finishing said tube, and means for dismounting said capped tube from said mandrel.
17. In a tube finishing and capping machine, means for supporting a tube, means for mounting a tube on said supporting means, means for finishing said tube, means for capping said tube, and means for dismounting said capped tube from said supporting means.
18. In a tube capping and finishing machine, a cap hopper, means for delivering a single cap at a time from said hopper into capping position, a tube reservoir, a carriage, means for feeding a single tube at a time to said carriage, means for supporting a tube, means for operating said carriage for mounting a tube on said supporting means, and means for operating said cap delivering means for causing said delivering means to cap said tube.
19. In a tube capping and finishing machine, a cap hopper, means for delivering a single cap at a time from said hopper into capping position, a tube reservoir, a carriage, means for feeding a single tube at a time to said carriage, means for supporting a tube, means for operating said carriage for mounting a tube on said supporting means, and means for operating said cap delivering means for causing said delivering means to cap said tube.
20. In a tube finishing machine, a mandrel, a tip on said mandrel hexagonal in cross section, and means for mounting a tube on said mandrel, whereby said hexagonal tip engages the inside of the tip of said tube.
21. In a tube capping and finishing machine, a cap hopper, means for withdrawing a cap from said hopper, means free to rotate, adapted alternately to grip and to release said cap, a revolute mandrel, means for mounting a tube on said mandrel, and means for causing said cap gripping means to feed a cap axially to said tube.
22. In a tube capping and finishing machine, a cap hopper, means for withdrawing a cap from said hopper, means free to rotate, for alternately gripping and releasing said cap, a revolute mandrel, means for mounting a tube on said mandrel, means for finishing said tube, means for causing said cap gripping means to feed a cap to said tube and means for dismounting said capped tube.
23. In a tube finishing and capping machine, revolute means for supporting a tube, a tube reservoir, means for mounting a tube on said supporting means, means for delivering a single tube at a time to said tube mounting means from said reservoir, and means for capping said tube comprising means for axially feeding a cap to said tube.
24. In a tube finishing and capping machine, revolute means for supporting a tube, a tube reservoir, means for mounting a tube on said supporting means, means for delivering a single tube at a time to said tube mounting means from said tube reservoir, means for finishing said tube, means for capping said tube comprising means for axially feeding a cap to said tube, and means for dismounting said capped tube.
25. In a tube capping and finishing machine, means for feeding a single tube at a time comprising a tube slide tilted longitudinally and transversely, a pair of gates positioned respectively rearwardly and forwardly of the lowermost tube in said slide and means for alternately moving the rearward and forward gates alternately in opposite directions, means for supporting a tube and means for mounting a tube on said supporting means.
26. In a tube capping and finishing machine, means for feeding a single tube at a time comprising a tube slide tilted longitudinally and transversely, a pair of gates positioned respectively rearwardly and forwardly of the lowermost tube in said slide and means for alternately moving the rearward and forward gates alternately in opposite directions, means for supporting a tube and means for mounting a tube on said supporting means.

- tudinally and transversely, a pair of gates positioned respectively rearwardly and forwardly of the lowermost tube in said slide, and means for alternately moving the rearward and forward gates alternately in opposite directions, means for supporting a tube, means for finishing said tube, means for capping said tube, and means for dismounting said capped tube.
27. In a tube capping and finishing machine, a cap hopper, means for delivering a single cap at a time from said hopper into capping position, a tube reservoir, a carriage, means for feeding a single tube at a time to said carriage comprising a tube slide tilted longitudinally and transversely, a pair of gates positioned respectively rearwardly and forwardly of the lowermost tube in said slide, and means for alternately moving the rearward and forward gates alternately in opposite directions, means for supporting a tube, means for operating said carriage for mounting a tube on said supporting means, means for finishing said tube, means for operating said cap delivering means for causing said delivering means to cap said tube, and means for dismounting the capped tube from said supporting means.
28. In a tube capping machine, a cap hopper, a chute, means for arranging the caps in said chute in a single vertical row, and means for withdrawing the lowermost cap of the row and for delivering said cap into capping position comprising a bearing, a pair of fingers pivoted to said bearing, a longitudinally slideable shaft on which said bearing is revolubly mounted, a collar slidably mounted on said shaft and operatively connected to said fingers for opening and closing said fingers, a push rod arranged coaxially with and carried by said shaft for longitudinal movement in said shaft, a second push rod adapted to engage the lowermost cap of the row for pushing said cap out of said chute and into engagement with said first push rod, and means for operating said collar and for moving said shaft and the parts carried thereby, bodily as a unit.
29. In a tube capping and finishing machine, means for delivering a cap into capping position comprising a longitudinally slideable shaft, a bearing revoluble on said shaft, a pair of fingers pivoted to said bearing, a spring pressed push rod arranged coaxially with, slideable in, and mounted for operative connection to said shaft, means for pushing a cap against said rod for sliding said shaft, and means operatively connected to said fingers for closing said fingers on the sliding of said shaft in one direction and for opening said fingers on the sliding of said shaft in the opposite direction.
30. In a tube capping machine, a grooved chute having an aperture at the lower end thereof, for arranging tube caps in a single row, and means for withdrawing the lowermost cap of the row from said chute through the aperture thereof, comprising a rod for pushing said lowermost cap through said aperture, a spring pressed rod against which said cap is pushed and a pair of freely revoluble fingers arranged coaxially with and operated by said spring pressed rod to grip said cap.
31. In a tube finishing and capping machine, a cap hopper, a chute, means for delivering said caps in a single row to said chute, freely rotatable capping fingers, means for delivering the lowermost cap in said row to said fingers, means for closing said fingers about said cap on the delivery of said cap within reach of said fingers, tube supporting means, tube finishing means, and means for delivering said cap into alignment with said tube, for closing said fingers more tightly about said cap, for moving said cap on to the finished end of said tube, and for withdrawing said fingers from the capped tube.
32. In a tube capping machine, a cap hopper, a cap chute, means for delivering caps in a single row to said chute, capping fingers, means for feeding the lowermost cap of said row to said fingers, means for closing said fingers about said cap, for delivering said cap into capping position, and for withdrawing said fingers from said cap, a mandrel, a tube carriage, means operatively connected to said carriage for moving said carriage toward said mandrel for mounting a tube on said mandrel, means for withdrawing said carriage from said mandrel, and means for finishing a tube, operated by said carriage at the completion of the mounting operation.
33. In a tube capping and finishing machine, a cap hopper, means for delivering a cap into capping position, a tube reservoir, means for delivering a single tube at a time from said reservoir into capping position comprising a tube slide tilted longitudinally and transversely, a pair of gates positioned each respectively rearwardly and forwardly of the lowermost tube in said slide and means for lowering one of said gates and for substantially simultaneously raising the other of said gates, a hollow mandrel, means for mounting said tube on said mandrel, means for finishing said tube, and means for blowing air through said mandrel for dismounting said tube.
34. In a tube capping and finishing machine, a cap hopper, a grooved chute having an aperture at the lower end thereof, for arranging the caps in a single row therein, means for withdrawing the lowermost cap of the row through the aperture of said chute comprising a rod for pushing said lowermost cap through said aperture, a

- spring pressed rod against which said rod is pushed, and a pair of fingers adapted to grip and to release said cap alternately, a carriage, means for feeding a single tube at a time to said carriage, means for supporting a tube, means for drawing said carriage toward said supporting means for mounting a tube on said supporting means, means for finishing said tube, means for causing said fingers to cap said tube and means for dismounting the capped tube.

35. In a tube finishing and capping machine, a revolute mandrel, and means for mounting a collapsible tube on said mandrel comprising a carriage V-shaped in cross section, means on said carriage for engaging the end of said tube, means for drawing said carriage toward said mandrel at accelerated speed, and means for drawing said carriage away from said mandrel after said tube has been mounted.

36. In a tube finishing and capping machine, a hollow revolute mandrel, a polygonal tip on said mandrel, a V-shaped carriage adapted to receive a tube, means for drawing said carriage toward said mandrel at accelerated speed for mounting the entire tube firmly in said mandrel, means for withdrawing said carriage, means for finishing said tube, actuated by said carriage at the end of the mounting operation, means for capping said tube during the rotation of said mandrel, and means for blowing air through said mandrel for dismounting said tube.

37. In a tube finishing and capping machine, a hollow revolute mandrel, means for mounting a tube on said mandrel, means operatively connected to said tube mounting means for finishing said tube at the end of the mounting operation, means for capping said tube and a pump for blowing air through said mandrel for dismounting said tube from said mandrel after capping.

40 38. In a tube finishing and capping machine, a revolute mandrel having a longitudinal opening therethrough, a polygonal end on said mandrel, a carriage V-shaped in cross section, adapted to receive a tube, means for feeding a single tube at a time to said carriage, weights for drawing said carriage toward said mandrel at accelerated speed until the polygonal tip of said mandrel is forced into the tip of said tube, a clutch operated by said carriage at the end of its tube mounting stroke, means for finishing said tube controlled by said clutch, means for capping said tube, and means for blowing air through the opening in said mandrel for dismounting said tube.

45 39. In a tube finishing and capping machine, a cap hopper, means for delivering a cap from said hopper into capping position, comprising a pair of swingable fingers, a substantially horizontal shaft carrying said

50 fingers, a collar slidable on said shaft operatively connected to said fingers, means for exerting a predetermined degree of pressure on said shaft for resisting longitudinal movement of said shaft, a substantially vertical shaft carrying said horizontal shaft, means operatively connecting said vertical shaft and said collar for causing said collar to open and close said fingers on the longitudinal movement of said vertical shaft and means for resisting movement of said vertical shaft until predetermined longitudinal movement of said horizontal shaft takes place.

55 40. In a tube finishing and capping machine, a substantially horizontal shaft, a substantially vertical shaft and means carried by said horizontal shaft and actuated by the longitudinal movement of said vertical shaft for gripping and for releasing a cap and for delivering said cap to the capping position.

60 41. In a tube finishing and capping machine, a cap hopper, a chute, a push rod positioned normally, to support the row of caps in said chute, a pair of revolute fingers, means for operating said rod for forwarding the lowermost cap of the row from said chute toward said fingers, and means operated on the movement of said lowermost cap by said rod for causing said fingers to close about said cap.

65 42. In a tube finishing and capping machine, a pair of fingers, means for delivering a single cap at a time within reach of said fingers, a vertical shaft, operatively connected to said fingers, and means for reciprocating said vertical shaft for causing said fingers to grip said cap, to move to the capping position, to advance the cap axially for capping the tube, to open said fingers and withdraw from the capped tube, and to return to the vertical position successively in the order named.

70 43. In a tube finishing and capping machine, a revolute mandrel, a polygonal end on said mandrel, and means for mounting a tube on said mandrel comprising a carriage, and means for drawing said carriage toward said tube at accelerated velocity until stopped, whereby said tube is mounted on said mandrel and the end of said tube is pushed firmly on said polygonal end of said mandrel for rotation therewith.

75 44. In a tube capping and finishing machine, means for supporting a tube, means for mounting a tube on said supporting means, means for finishing said tube, a clutch controlling said finishing means, and means operated by said mounting means for throwing said clutch, after said tube has been mounted on said supporting means.

80 45. Means for capping a tube comprising means for rotating said tube and means, free to rotate with said tube, for feeding a cap

axially to said tube, and for exerting suddenly applied pressure on said cap near the completion of the capping operation.

46. In a tube finishing and capping machine, revolute means for supporting a tube, a tube reservoir, means for mounting a tube on said supporting means, and means for capping said tube comprising means for axially feeding a cap to said tube.

47. In a tube finishing and capping machine, revolute means for supporting a tube, a tube reservoir, means for delivering a single tube at a time from the reservoir to the tube supporting means, and means for capping said tube comprising means for creating relative axial movement between the cap and tube.

JOSEPH H. KONIGSBERG.
